UNITED STATES PATENT OFFICE.

HINSDALE SMITH, OF SOUTH HADLEY, MASSACHUSETTS.

DESIGN FOR AN AUTOMOBILE-BODY.

47,630.

Specification for Design.

Patented July 20, 1915.

Application filed April 2, 1915. Serial No. 18,853. Term of patent 14 years.

To all whom it may concern:

Be it known that I, HINSDALE SMITH, a citizen of the United States, residing at South Hadley, in the county of Hampshire and State of Massachusetts, have invented a new, original, and ornamental Design for an Automobile-Body, of which the following is a specification, reference being had to the accompanying drawing, forming part thereof, in which the body is shown in perspective.

I claim:

The ornamental design for an automobile body as shown.

In testimony whereof I affix my signature in presence of two witnesses.

HINSDALE SMITH.

Witnesses:

E. J. WHEELER,
A. S. BOWEN.
